COMBINED DISPENSING AND DISPLAY STAND FOR MERCHANDISE

Max Julius Wolff, Nidau, Switzerland, assignor to Saphirwerk AG Nidau, Nidau, Canton of Berne, Switzerland

Filed Mar. 7, 1969, Ser. No. 16,131

Claims priority, application Switzerland Sept. 18, 1968

Term of patent 14 years

Int. Cl. D6—06

U.S. Cl. D6—189

FIG. 1 is a front perspective view of a combined dispensing and display stand for merchandise embodying my new design, the rear being plain and unornamented; and

FIG. 2 is an enlarged fragmentary front perspective view of the upper left corner thereof.

The broken line representation of merchandise cards in FIGS. 1 and 2 is for purposes of illustration only.

What is claimed:

The ornamental design for a combined dispensing and display stand for merchandise, substantially as shown and described.
